BRAIDING STAND

Arthur W. Prescott, Kittery, Maine

Application November 21, 1952, Serial No. 321,805

3 Claims. (Cl. 87—33)

This invention relates to a device for braiding and forming strands and more particularly to a device for holding the strands in a secure manner so as to produce a firm and even braid.

The primary object of this invention resides in the provision of a braiding stand that is adapted to releasably hold the strands of the braid to be formed in a secure manner while satisfactorily supporting a good proportion of the work on the work table associated with the device.

A further object of the invention resides in the pedal actuated means for engaging and disengaging the clamp member for holding the strands firmly in place.

Still further objects of the invention reside in the provision of a braiding stand that is strong, durable, highly efficient in operation, simple in construction and manufacture, of pleasing appearance, and capable of being produced at a relatively low cost.

These, together with the various ancillary objects of the invention which will become apparent as the following description proceeds, are attained by this braiding stand, a preferred embodiment of which has been illustrated in the accompanying drawings, by way of example only, wherein:

Figure 1 is a perspective view of the braiding stand comprising the present invention;

Figure 2 is an enlarged vertical sectional view as taken along the plane of line 2—2 in Figure 1;

Figure 3 is a vertical sectional view taken along the plane of line 3—3 in Figure 2, showing the construction of the pedal actuated means for operating the clamping member;

Figure 4 is a horizontal sectional view as taken along the plane of line 4—4 in Figure 3, showing the manner in which the pedal is mounted on the frame of the invention;

Figure 5 is a vertical sectional view as taken along the plane of line 5—5 in Figure 2, showing the construction of the guides for preventing rotary movement of the clamping members; and

Figure 6 is a sectional detail as taken along the plane of line 6—6 in Figure 2, showing in particular the construction of an attachment for the invention comprising a bracket for holding a pair of shears.

With continuing reference to the accompanying drawings wherein like reference numerals designate similar parts throughout the various views, reference numeral 10 generally designates one of a pair of legs, the other being designated by reference numeral 12. The legs 10 and 12 form a portion of a frame which includes base members 14 and 16 which are secured to the legs 10 in spaced parallel relationship. A footboard 18 is secured to the base members 14 and 16 and extends therebetween. Secured to the legs 10 and 12 between the base members 14 and 16 are vertically extending frame members 20 and 22.

The frame members 20 and 22 extend vertically upward and have secured to their upper edges a work table 24.

2

Extending between the side frame members 20 and 22 are panels 26 and 28 which together with the transverse panel 30 form a casing. Extending between the transverse panel 30 and the work table 24 is a housing 32 of box-like configuration. The outer panel of the casing 32 is removable in order that the working parts carried therein be readily accessible. Furthermore, the panel 26 is also detachably secured in any convenient manner.

A clamp member 34 is secured to the upper end of a plunger 36 which extends through a suitable aperture 38 in the table top 24. The plunger 36 extends through the housing 32 and through the transverse frame member 30. The plunger 36 is formed with a rounded semi-circular end 40 which is adapted to engage within a recess 42 formed in a lever bar 44 which is pivotally mounted on a shaft 46 extending between the panels 26 and 28.

A collar 48 is secured to the plunger 36 by means of a set screw 50 or other means for readily adjusting and detachably securing the collar 48. A coil spring 52 biases the collar 48 and the undersurface of the table top 24. The collar 48 is provided with notches 54 and 56 therein for reception of guides 58 and 60 which are made from suitable dowels and secured to the table top 24 and the transverse member 30.

Pivotally secured to a shaft 62 carried by a block 64 secured by screws 66 or other suitable means to the leg 12 is a pedal 68 having a foot engaging tread 70 at one end. By means of an eye bolt 72 secured to the pedal 68 centrally thereof and an eye 74 depending from the lever bar 44, a connecting rod 76 is terminally secured to the pedal 68 and the lever bar 44.

In operation, the spring 52 continuously urges the collar 48 downwardly thus causing the clamping member 34 to resiliently engage a strand, such as indicated at 80, between itself and the work table 24. After braiding the strands, the completed portion of the braid is then carried across the working table until the end of the completed portion may be placed under the clamp 34. This is permitted by depressing the pedal 68 thus pulling one end of the lever bar 44 down which presses the plunger 36 upwardly against the force of the spring 52. The plunger 36 is maintained from rotating by means of the slots 54 and 56 in the collar engaging the guides 58 and 60.

There is provided a substantially U-shaped bracket 82 having flanges 84 and 86 which are secured to the vertically extending frame member 22 by means of screws 88 or any other suitable fastener. The bracket 82 is adapted to support a pair of shears within easy reach of the operator. Furthermore, it is to be understood that the space between the transverse member 30 and the top 24 may be readily used for storage of cloth strips, thread, or any other suitable material.

Since from the foregoing, the construction and advantages of this braiding apparatus are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be readily resorted to that fall within the scope of the appended claims.

What is claimed as new, is as follows:

1. A braiding stand comprising a frame, a work table carried by said frame, a clamp member, a plunger secured to said clamp member extending through said table, a collar on said plunger, resilient means biasing said collar and said work table to urge said clamp member against said table, and actuating means engaging said plunger to raise said plunger, vertically extending guides in said casing, said collar engaging said guides.
2. A braiding stand comprising a frame, a casing sup-

ported by said frame, a work table carried by said frame, a clamp member, a plunger secured to said clamp member, said plunger extending through said table and into said casing, a collar on said plunger, resilient means biasing said collar and said work table to urge said clamp member against said table, and actuating means engaging said plunger to raise said plunger, said actuating means including a pedal pivotally mounted on said frame, a lever bar pivotally secured to said frame, said lever bar engaging said plunger, and a connecting rod terminally secured to

10

3. A braiding stand comprising a frame, a work table carried by said frame, a clamp member, a plunger secured to said clamp member extending through said table, a collar on said plunger, resilient means biasing said collar and said work table to urge said clamp member against said
